(57) **CLAIM**

The ornamental design for an ionizer controller module, as shown and described.

DESCRIPTION

FIG. 1 is a front, top, left side perspective view of an ionizer controller module according to a first embodiment of our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom elevational view thereof;

FIG. 7 is a top elevational view thereof;

FIG. 8 is a front, bottom, right side perspective view thereof;

FIG. 9 is a back, bottom, left side perspective view thereof;

FIG. 10 is a front, top, left side perspective view of an ionizer controller module according to a second embodiment of our design;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a bottom elevational view thereof;

FIG. 16 is a top elevational view thereof;

FIG. 17 is a front, bottom, right side perspective view thereof; and,

FIG. 18 is a back, bottom, left side perspective view thereof.
